UNITED STATES PATENT OFFICE

ADOLPH G. LOTTER, OF MILWAUKEE, WISCONSIN, ASSIGNOR, BY MESNE ASSIGNMENTS, TO STATIONERS LOOSE LEAF CO., OF MILWAUKEE, WISCONSIN, A CORPORATION OF WISCONSIN

LOOSE-LEAF BINDER

Application filed May 21, 1928. Serial No. 279,513.

This invention relates to loose leaf binders of the character commonly used in connection with visible record systems in which the leaves are so arranged within the binder that their lower and upper edges are staggered so that data on the upper portions of the leaves is visible at all times.

In the visible record system of bookkeeping, it is frequently necessary to insert or remove leaves from the book, in which case it is necessary to shift some of the leaves to maintain their staggered relation at all times. Numerous devices for accomplishing this result have been proposed which are either expensive to manufacture or do not permit of great flexibility in the insertion or removal of the leaves and this invention contemplates as an object the provision of an improved binder for use in connection with visible record systems which has great flexibility as to the ability to shift one or more leaves in either direction upon the removal or insertion of other leaves.

Another object of this invention resides in the provision of an improved binder of the character described which is so constructed mechanically as to be easily operated and which will not be readily damaged by the rough handling to which devices of this character are normally subjected.

Heretofore binders adapted for use with visible record systems have had their series of impaling prongs staggered with respect to each other by longitudinally shifting either one or both series and this invention has as a further object the provision of an improved manner of mounting the impaling prongs whereby they are rotated to stagger their adjacent ends to facilitate shifting of the leaves.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated several complete examples of the physical embodiment of my invention constructed according to the best modes I have so far devised for the practical application 55 of the principles thereof, and in which:

Figure 1 is a top plan view of a binder embodying my invention with the cover and leaves in open position;

Figure 2 is a top plan view of the binder 60 back piece with the covers and leaves removed and illustrating the impaling prongs in open position and swiveled prior to being closed on each other to position their ends in staggered relation;

Figure 3 is a view similar to Figure 1 illustrating the binder closed with the impaling-prong ends staggered;

Figure 4 is a view similar to Figure 2 with parts broken away and in section to illustrate details of construction;

Figure 5 is a transverse, sectional view, taken through Figure 1 on the plane of the line 5—5; and

Figure 6 is a longitudinal, sectional view, 75 taken through Figure 1 on the plane of the line 6—6.

Referring now more particularly to the accompanying drawings, in which like numerals designate like parts throughout the 80 several views, 5 designates a loose leaf binder back plate having covers 6 and 7 hinged to its opposite edges, as at 8, the back plate being preferably formed with its marginal edges 9 on a higher plane than its central 85 portion and being closed by a base plate 10 fixed thereto by rivets or other means 11.

The base plate 10 has a lazy tong device mounted thereon which consists of a pair of intersecting levers 12 and 13 pivotally connected at their point of intersection by a rivet or pin 14 passing therethrough and through the back plate, base plate and a slidably mounted latch or locking member 15, to be later described. The pin 14 is riveted 90 over the back plate and the latch member 15 and has a spacing collar 16 thereon to maintain the lazy tong members and the latch member in spaced relation, the aperture 17 of the latch member through which 100

the pin 14 passes being elongated to permit limited longitudinal movement of the member, as will be later described.

A pair of smaller levers or links 18 and 19 having their outer ends pivotally connected, as at 20, is connected with the levers 12 and 13 at each side of their pivotal connection 14, by rivets 21 or the like, passing through the inner ends of the levers 18 and 19 and 10 through the levers 12 and 13, at points equi-spaced from the pivot pin 14, the pivots 20 passing through elongated apertures 22 in the base plate 10 to guide their movements and insure the movement of the adjacent ends 15 of levers 12 and 13 in the same plane, as will be readily apparent.

The ends of levers 12 and 13 are pivotally connected with a pair of sidewise, movable slide plates or members 23 and 24 by rivets 25 that pass through elongated apertures 26 in the levers 12 and 13 to accommodate the necessary play and the sidewise movements of the side plates, which are maintained parallel at all times by the lazy tong device. 20 The ends of the members 23 and 24 are guided by upwardly and inwardly directed flanges 27 and 27' on the ends of the base plate 10, the slide members being provided with downwardly extended transverse beads or ribs 28 30 which space them from the mounting plate a distance equal to the combined thickness of the levers 12 and 13 and insure the proper guiding of their extreme ends 29 by the end flanges 27 and 27'.

35 Two series of cooperating impaling prongs or rings 30 and 31 are associated with the slide members 23 and 24, respectively, the series 30 being riveted, welded or otherwise secured, as at 32, to a mounting plate 33 secured, as at 34, to the slide member 23 and having its outer marginal edge flanged downwardly, as at 35, to provide a neat external appearance and to eliminate sharp, ungainly edges. The prongs of the series 31 40 are riveted or otherwise secured, as at 36, to prong mounting plates 37 pivotally secured to the slide member 24 by rivets or other means 38.

A cover and prong actuating plate 39 is 50 disposed over the series of plates 37, being pivotally connected with each plate 37 at their ends opposite the pivots 39 by pivot pins or rivets 40, the plate 39 having apertures 41, through which the prongs 31 pass. 55 The plate 39 is slidably secured to the slide member 24 for transverse movement therewith but longitudinal movement independently thereof by rivets 42 passed through elongated slots 43 in the plate 39, the plates 37 adjacent the pivot pins or rivets 42 being 60 cut away, as at 44, so that their pivotal or swivel movement is not interfered with.

The plates 24 and 33 have upwardly extending lugs or tongues 45 struck from their 65 inner edge portions adjacent each end which

are adapted to be engaged in locking recesses 46 formed in raised portions 47 of the locking member 15, the lugs 45 being of a height to permit the raised portion 47 to pass thereover when the member 15 is moved to unlocking position. The member 15 in addition to being guided by the pivot pin 14 is guided at its ends by rivets 48 and 49, the rivet 48 being fast to the base plate 10 and having a sleeve 50 thereon to maintain the proper spaced relation between the member 15 and the binder mechanism thereunder. The rivet 49 is likewise fast to the base plate and has an expansive spring 51 coiled thereabout to normally maintain the adjacent end portion 70 of the latch member, which is on a plane substantially even with the raised portions 47, against the head 52 of the rivet 49, the rivets 48 and 49 passing through elongated slots 53 in the member 15.

The opposite sides of slot 53 adjacent the rivet 49 have portions struck outwardly to provide upwardly curved projections or lugs 54 normally lying in the path of the rivet head 52 when the member 15 is in its locking position with the lugs 45 in the locking recesses 46. When it is desired to move the member 15 to unlocked position the finger-engaging portion 55 on the end of the member 15 adjacent the pin 49 is depressed to flex or bend 80 the same sufficient to position the lugs 54 beneath the head 52 and permit movement of the member 15 to unlocked position.

The horizontal portion 56 of the guide flange 27 has notches or grooves 57 and 58 in its opposite ends in which studs or lugs 59 and 60 carried by the plates 33 and 39, respectively, are adapted to engage when the binder is closed with the ends of adjacent prongs in register so that the prongs of one series form continuations of the prongs of the other. The stud 59 and a stud 61, of which the stud 60 is a continuation, form means for facilitating the separation of the impaling prongs, and the stud 61 likewise provides means for oscillating or pivoting the series of prongs 31 to stagger their ends with respect to the ends of the adjacent impaling prongs of the other series.

The alternate prongs of each series are 115 provided with reduced extensions or projections 62 adapted to engage in sockets or recesses, not shown, in the ends of the adjacent prongs of the opposite series when the binder is in the normal position of use illustrated in Figure 1. When the series of prongs 31 are diagonally disposed and the binder closed in the manner illustrated in Figure 3, the ends of the impaling prongs of one series overlap, with those of the other series, as their ends are cut on a bias, so that record sheets or leaves 63 on one series of impaling prongs may be readily slid thereover onto the impaling prongs of the other series without difficulty, the sheets in moving 120 125 130

from one series of prongs to the other while in the staggered relation being shifted longitudinally of the binder to accommodate the insertion or removal of one or more leaves.

5 When it is desired to effect the shifting of one or more of the leaves, the binder is opened as illustrated in Figure 1 and the latch member operated to release the mechanism by depressing its end 55 and moving it to the right with reference to Figure 6. The studs 59 and 61 are then engaged and moved apart to separate the series of impaling prongs and disengage the studs 59 and 60 from their recesses 57 and 58. The stud 61 is then moved inwardly to slide the plate 39 longitudinally which oscillates or moves the members 37 on their pivots 38 to dispose the impaling prongs 31 angularly with respect to the impaling prongs 30, as illustrated in Figure 2.

10 The studs 59 and 61 are then moved toward each other so that the prongs of the series are disposed in staggered relation with their ends overlapping, as illustrated in Figure 3, when the transfer of the leaves from one series of prongs to the other may be readily effected. The binder may be locked in this position by moving the member 15 to the left with respect to Figure 6 as illustrated in

15 Figure 3.

The stud 60 engages a finger 64 at its inner side when in the position illustrated in Figure 2, so that the shifting of the plate 39 and consequently the prongs 31 is restrained until the parts have been unlocked by operation of the member 15 and moved to the separated position. The horizontal portion 65 of the guide 27' has its side adjacent the plate 39 cut away, as at 66, to accommodate longitudinal sliding movement of said plate, to angularly position the prongs 31 and the slide member 24.

20 After the sheets have been shifted, the binder is unlocked, the prongs separated and the plate 39 moved to straighten the prongs 31, the binder being then closed to interlock the ends of adjacent prongs, as illustrated in Figure 1.

25 From the foregoing description, taken in connection with the accompanying drawings, it will be readily apparent to those skilled in the art to which an invention of the character described apertains, that I provide a novel and improved binder specially adapted for use in connection with visible record systems in which the impaling prongs are oscillated or rotated to effect the staggering of the prongs of one series with respect to the other for the purpose of shifting the record sheets; which may be readily locked in either normal closed position or in closed position with the impaling prongs staggered, and one in which the binder must be unlocked and moved to full open position before the rotation of the prongs can be effected.

What I claim as my invention is:

1. In a loose leaf binder adapted to contain record leaves, two series of impaling prongs, mounting means for the series of impaling prongs, said mounting means being movable in a common plane to separate the series of impaling prongs and permit removal or addition of record leaves, and means mounting the impaling prongs of one series for angular movement to shift their free ends with respect to the impaling prongs of the other series to effect longitudinal shifting of the leaves with respect to each other.

2. In a loose leaf binder adapted to contain record leaves, a base, two series of impaling prongs associated with the base, members for supporting the series of impaling prongs, means whereby one of said members has transverse movement on the base, means pivotally mounting the impaling prongs of one series on said last-mentioned member, and means for simultaneously moving said impaling prongs carried by the transversely movable member about their pivotal mounting to stagger their ends with respect to the ends of the impaling prongs of the other series.

3. In a loose leaf binder adapted to contain record leaves, a base, two series of impaling prongs associated with the base, members for supporting the series of impaling prongs, means whereby one of said members has transverse movement on the base, means pivotally mounting the impaling prongs of one series on said last-mentioned member, means for simultaneously moving said impaling prongs carried by the transversely movable member about their pivotal mounting to stagger their ends with respect to the ends of the impaling prongs of the other series, and means for securing the pivotally mounted impaling prongs against pivotal movement when the members are closed on each other.

4. In a loose leaf binder adapted to contain record leaves, a base, two series of impaling prongs associated with the base, members for supporting the series of impaling prongs, means whereby one of said members has transverse movement on the base, means pivotally mounting the impaling prongs of one series on said last-mentioned member, means for simultaneously moving said impaling prongs carried by the transversely movable member about their pivotal mounting to stagger their ends with respect to the ends of the impaling prongs of the other series of impaling prongs, means for securing the pivotally mounted impaling prongs against pivotal movement when the members are closed on each other, and means for securing the transversely movable member against transverse movement.

5. In a loose leaf binder adapted to contain record leaves, a base member, a pair of slide

members associated with the base member for transverse movement to and from a position with their inner longitudinal edges adjacent, a series of impaling prongs associated with one slide member, a series of impaling prongs associated with the other slide member for movement angularly thereof, and means for simultaneously moving said impaling prongs to and from angular position.

6. In a loose leaf binder adapted to contain record leaves, a base member, a pair of slide members associated with the base member for transverse movement to and from a position with their inner longitudinal edges adjacent, a series of impaling prongs associated with one slide member, a series of impaling prongs associated with the other slide member and movable to and from positions at an angle with the impaling prongs of the first-mentioned series, means for simultaneously moving said impaling prongs to and from said position, and means securing the second-mentioned series of impaling prongs against movement when the slide members are closed on each other.

7. In a loose leaf binder adapted to contain record leaves, a base member, a pair of mounting plates associated with the base member for transverse movement to and from a position with their inner longitudinal edges substantially meeting, a series of impaling prongs rigidly associated with one mounting plate, a series of impaling prongs associated with the other mounting plate and movable to and from positions at an angle with the rigidly mounted impaling prongs, means for simultaneously moving said impaling prongs to and from the said position, means securing said second-mentioned series of impaling prongs against movement when the mounting plates are closed on each other, and means for releasably securing the mounting plates with their longitudinal edges adjacent.

8. In a loose leaf binder adapted to contain record leaves, a base member, two series of impaling prongs associated with the base member, a slide member, and a series of mounting plates pivotally carried by said slide member, the impaling prongs of one series being fixed one to each of said mounting plates whereby pivotal movement of the mounting plates positions the impaling prongs carried thereby angularly with respect to the impaling prongs of the other series.

9. In a loose leaf binder adapted to contain record leaves, a base member, two series of impaling prongs associated with the base member, a slide member, a series of mounting plates pivotally carried by said slide member, the impaling prongs of one series being fixed one to each of said mounting plates whereby pivotal movement of the mounting plates positions the impaling prongs carried thereby angularly with respect to the impaling prongs of the other series, and means for simultane-

ously moving said mounting plates on their pivots.

10. In a loose leaf binder adapted to contain record leaves, a base member, two series of impaling prongs associated with the base member, a slide member, a series of mounting plates pivotally carried by the slide member, the impaling prongs of one series being fixed one to each of said mounting plates whereby pivotal movement of the mounting plates positions the impaling prongs carried thereby angularly with respect to the impaling prongs of the other series, means for simultaneously moving said mounting plates on their pivots, and means for transversely moving one series of impaling prongs.

11. In a loose leaf binder adapted to contain record leaves, a base member, a pair of slide members associated with the base member for transverse movement, a plurality of mounting plates pivotally carried by one slide member, a series of impaling prongs fixed one to each mounting plate at a point spaced from its pivot, a series of impaling prongs associated with the other slide member, and means for pivoting said mounting plates to stagger the ends of said first series of impaling prongs with respect to the ends of the adjacent prongs of the second series.

12. In a loose leaf binder adapted to contain record leaves, a base member, a pair of slide members associated with the base member for transverse movement, a plurality of mounting plates pivotally carried by one slide member, a series of impaling prongs fixed one to each mounting plate at a point spaced from its pivot, a series of impaling prongs associated with the other slide member, a cover plate member longitudinally slidably associated with the slide member supporting said mounting plates and having elongated apertures through which said first series of impaling prongs pass, and means pivotally connecting each mounting plate with said cover plate whereby longitudinal movement of the cover plate simultaneously pivots the mounting plates to stagger the ends of said first series of impaling prongs with respect to the ends of the adjacent prongs of the second series.

13. In a loose leaf binder adapted to contain record leaves, a base member, a pair of slide members associated with the base member for transverse movement, a plurality of mounting plates pivotally carried by one slide member, a series of impaling prongs fixed one to each mounting plate at a point spaced from its pivot, a series of impaling prongs associated with the other slide member, a cover plate member longitudinally slidably associated with the slide member supporting said mounting plates and having elongated apertures through which said first series of impaling prongs pass, means pivotally connecting each mounting plate with said cover plate

whereby longitudinal movement of the cover plate simultaneously pivots the mounting plates to stagger the ends of said first series of impaling prongs with respect to the ends of the adjacent prongs of the second series, and means for securing said cover plate against movement.

14. In a loose leaf binder adapted to contain record leaves, a base member, a pair of slide members associated with the base member for transverse movement, a plurality of mounting plates pivotally carried by one slide member, a series of impaling prongs fixed one to each mounting plate at a point spaced from its pivot, a series of impaling prongs associated with the other slide member, a cover plate member longitudinally slidably associated with the slide member supporting said mounting plates and having elongated apertures 23 through which said first series of impaling prongs pass, means pivotally connecting each mounting plate with said cover plate whereby longitudinal movement of the cover plate simultaneously pivots the mounting plates to stagger the ends of said first series of impaling prongs with respect to the ends of the adjacent prongs of the second series, means for securing said cover plate against movement when the slide members are adjacent each other, and means securing the slide members against movement apart.

15. In a loose leaf binder adapted to contain record leaves, a base member, a pair of slide members associated with the base member for transverse movement to and from a position with their inner edges substantially abutting, means for guiding said slide members in their movements to and from each other, a mounting plate carried by one slide member, a series 40 of impaling prongs carried by said mounting plate, a series of mounting plates pivotally carried by the other slide member, a second series of impaling prongs carried one by each or said pivotally mounted mounting plates, a 45 cover plate secured over said pivotally mounted mounting plates and slidably associated with the adjacent slide member, and means connecting said cover plate with said pivotally mounted mounting plates whereby sliding of the cover plate pivots the said series of mounting plates to dispose the impaling prongs associated therewith angularly with respect to the first series of impaling prongs.

16. In a loose leaf binder adapted to contain record leaves, a base member, a pair of slide members associated with the base member for transverse movement to and from a position with their inner edges substantially abutting, means for guiding said slide members in their 60 movements to and from each other, a mounting plate carried by one slide member, a series of impaling prongs carried by said mounting plate, a series of mounting plates pivotally carried by the other slide member, a second 65 series of impaling prongs carried one by each

of said pivotally mounted mounting plates, a cover plate secured over said pivotally mounted mounting plates and slidably associated with the adjacent slide member, means connecting said cover plate with said pivotally mounted mounting plates whereby sliding of the cover plate pivots the said series of mounting plates to dispose the impaling prongs associated therewith angularly with respect to the first series of impaling prongs, means for securing said cover plate against shifting movement, and means for securing the slide members against movement apart.

17. In a loose leaf binder, two series of impaling prongs, mounting means movable toward and away from each other in a common plane and each having one end of the prongs of one series connected therewith, and means for moving the impaling prongs of one series to position their free ends out of transverse alignment with their mounting ends to facilitate shifting of leaves.

18. In a loose leaf binder, a base member, a mounting member movable transversely over the base member, impaling prongs having one end connected with the mounting member, and means for moving the free ends of the impaling prongs out of transverse alignment with their mounting ends to facilitate shifting of leaves.

In testimony whereof I have hereunto affixed my signature.

ADOLPH G. LOTTER.
